DESIGN FOR A CRANE CAB

Ernest W. Taylor, Bay City, Mich., assignor to
The Industrial Brownhoist Corporation, Bay
City, Mich., a corporation of Ohio

Application September 16, 1938, Serial No. 79,940

Term of patent 14 years

To all whom it may concern:

Be it known that I, Ernest W. Taylor, a citizen of the United States and a resident of Bay City, in the county of Bay and State of Michigan, have invented a new, original, and ornamental Design for Crane Cabs, of which the following is a specification, reference being had to the accompanying drawings forming part thereof.

Fig. 1 is a side elevational view of a crane cab showing my new design.

Fig. 2 is a front elevational view.

Fig. 3 is a rear view of the crane cab.

Fig. 4 is a top plan view of the crane cab.

I claim:

The ornamental design for a crane cab, as shown.

ERNEST W. TAYLOR.
